COIN LOCK FOR ARTICLE DISPENSING MACHINES

Theodore Cerecke, Cuyahoga Falls, Ohio

Application June 13, 1952, Serial No. 293,305

4 Claims. (Cl. 194—61)

This invention relates to coin-operated article vending machines, and in particular relates to an improved coin lock for such machines.

Heretofore, coin locks of the type described have been provided which were satisfactory from the standpoint of normal operation of the vending machines. Dishonest persons, however, have found that by use of adhesive tape, chewing gum and other devices it is possible to adhere or jamb a coin in the usual rotatable coin holding plate, so that said plate may be rotated reversely past a coin-operated detent. In this manner it has been possible to fix a coin in the holding plate of a vending machine to permit repeated forward and reverse rotation of the operating means including said plate, until the machine has been emptied of its contents, thereby causing considerable loss to the owner of the machine.

One object of the present invention is to provide a simple, inexpensive improvement in a coin lock for vending machines, wherein a coin adhered or jammed in the coin-holding plate thereof will itself serve as stop means to prevent return rotation of the plate.

Other objects of the invention will be manifest from the following brief description and the accompanying drawings.

Of the accompanying drawings:

Figure 1 is a fragmentary front elevation of the improved coin lock, mounted on an article vending machine.

Figure 2 is a rear view of the lock, removed from the vending machine.

Figure 3 is a rear view of the lock with a rear plate of the lock housing removed and showing rotatable coin-receiving and coin-discharging positions, in full and chain-dotted positions, respectively.

Figure 4 is an enlarged fragmentary cross-section taken substantially on the line 4—4 of Figure 3.

Figure 5 is a view similar to Figure 3, but with the coin-receiving plate in a partly rotated position.

Figure 6 is a view corresponding to Figure 3, illustrating a modified form of the invention.

Figure 7 is an enlarged fragmentary cross-section taken substantially on the line 7—7 of Figure 6.

Referring to Figures 1 to 5 of the drawings, there is illustrated a coin-lock 10 having the features of the invention incorporated therein, the same being of the type to control dispensation of peanuts, chewing gum, candy or the like from a machine, a portion of which is indicated at 11 in Figure 1. The machine, generally, is of the class in which a coin is placed in a slot 12, permitting reciprocable operation a knob or handle 13 on a shaft 14 of operating means (otherwise not shown) to dispense a predetermined quantity of peanuts, for example, the operating means usually including a suitable spring-pressed device for yieldingly returning the operating means, including shaft 14 and knob 13, to the original Figure 1 positions thereof. That is, the knob 13 is yieldingly turned approximately 180 degrees to dispense the peanuts in known manner and then released to return to original position, automatically.

2

The lock 10 is contained in a casing 15, including a front plate 16 and a back plate 17 removably secured thereto, as by means of screws 18, 18. Laterally spaced rib portions 19, 19 on the front plate define with the inner face of the back plate a coin-receiving slot portion 12a at the upper portion of the lock, which normally registers with a coin-receiving slot or recess 20 in the edge of flat disc or plate 21 keyed on the shaft 14. Arcuate rib portions 22 and 23 on front plate 16 at laterally opposite sides of the disc 21 similarly define a cavity 24 in which the disc is rotatably received, the lower end of which opens downwardly into a coin-discharge opening 25 of the casing 10. A coin C inserted in slot portion 12a of the lock, and into the plate slot 20, is retained between the inner face of the back plate 17 and a flat surface of an annular rib 26 on the inner face of the front plate.

Angularly disposed slots 31 and 32 are cut in the arcuate rib portion 22 to receive and retain correspondingly angularly disposed elongated leaf-spring portions 33 and 34 of a V-shaped member 35 made from a length of spring strip material. Leaf-spring portion 33 extends upwardly in the space between the wall 22 and the edge of disc 21, and a leaf-spring portion 34 extends downwardly in the continuation of said space. Spring 33 extends to adjacent the coin-receiving slot 12a, as shown in Figures 3 and 5, in the path of movement of a protruding edge of a coin C, to press the coin to position fully within the coin slot 20 as disc 21 is rotated in said counter-clockwise direction. Similarly the spring portion 34 extends to adjacent the discharge opening 25. Intermediate these two retaining springs the rib portion 22 further serves to retain the coin C in place, as shown in Figure 5. In other words, rotating the disc 21 in counter-clockwise direction, as viewed in Figure 3, the inwardly projecting end 28 of spring 33 (Figure 2) normally rides upon the outer periphery of disc 21, but engages the right-hand edge of the plate slot 20 (see Figure 3) to stop such rotation, unless there is a coin C in the slot 20, in which instance the spring 33 rides over the coin and thereby allows the disc 21 to be rotated to carry the coin to discharge opening 25, where the coin is normally ejected by engagement thereof with a small protuberance 29 on the casing plate 16.

The free end of spring 34 is chamfered at 38 toward a downwardly presented shoulder 39 defined by a recessed portion 40 in the back plate 17, whereby a coin C, which for some reason is retained in plate slot 20 and reversely moved with disc 21 away from the discharge opening 25, will have a rearward or trailing edge portion thereof engaged by said chamfered portion. This results in said edge of the coin being lifted toward stop engagement with shoulder 39, as shown in chain-dotted lines in Figure 4, to stop further reverse rotation of disc 21.

In normal operation of the coin lock 10 shown in Figures 1 to 5 in a said vending machine 11, a coin C is placed in slot portion 12 and allowed to drop through slot 12a into registering slot 20 in disc 21, as shown in chain-dotted lines in Figure 3. Upon turning handle 13 a half revolution in clockwise direction, as viewed in Figure 1, the disc 21 will also rotate a half revolution to move the disc slot 20 to the lowermost position thereof shown in chain-dotted lines in Figure 3, where the protuberance 29 engages the inner edge portion of the coin to urge the same downwardly through discharge opening 25. The springs 33 and 34 serve to keep the coin in the disc slot 20 as the disc is rotated between the starting and discharge positions. This normal operation may be repeated as often as coins are placed in slot 12.

Should any dishonest scheme be utilized, however, to wedge or otherwise adhere a coin in the disc slot 20 with the idea in mind of accomplishing repeated operation of the coin lock 10 with the same coin, the scheme will be foiled upon the first return rotation of disc 20, because

the trailing edge of the adhered coin will ride up the chamfered end 38 of spring 34, into stop engagement with the shoulder 39 on casing part 17, as shown in Figure 4. In this stop position the free end of spring 34 extends in a plane at a substantial angle to a line tangent to the point of engagement of the free end of the spring with the coin. This, of course, prevents further operation of the vending machine until the owner thereof repairs the lock, but it also prevents loss due to repeated operation of the machine on one coin until the machine is empty of articles to be dispensed.

Figures 6 and 7 corresponding to Figures 3 and 4, respectively, illustrate a modified form of coin lock which is in all respects similar to the lock described above, except that the end of the spring part 34a, of V-shaped spring element 35a corresponding element 35, is squared at 40 to provide an inner, relatively sharp edge 41. Normal operation of this lock is as described above, but upon said dishonest use of the machine by adherence of a coin C₁ in disc slot 20a, the sharp edge 40 of the longitudinally relatively stiff spring 34a will dig into the rearward edge portion of the returning coin to prevent return rotation of disc 21a. The angle of the spring with respect to a line tangent to the point of contact of the end of the spring with the coin is substantially the same as described above in connection with spring 34 in Figure 3. As before, repair of the lock is required, but the articles in the machine are saved.

Thus, has been provided a very simple, economical device for preventing the aforementioned loss of goods from vending machines, which in the past created a very vexing problem for vending machine operators.

Other modifications of the invention may be resorted to without departing from the spirit thereof or the scope of the appended claims.

What is claimed is:

1. In an article dispensing machine of the type including operating means and coin-releasable detent for locking said operating means against forward rotation which would dispense the articles, a coin lock comprising a casing having a coin-receiving slot therein, a plate mounted in said casing to be rotatable with said operating means and having a coin-receiving recess in the edge thereof normally in registry with said coin-receiving slot in the locked position of the operating means, said casing having a coin-discharge opening for registry with said plate recess upon forward rotation of said plate with the operating means to a given discharge position thereof, said casing having guide portions intermediate said coin-receiving slot and coin-discharge opening for maintaining the coin in the coin-receiving recess of said plate, an elongated spring-pressed element anchored at one end in said casing to extend freely forwardly along the path of forward movement of a coin in said plate recess to have the free other end presented toward said coin-discharge opening, said element having a portion yieldingly engageable with a peripheral edge of the coin protruding from said plate recess as it moves forwardly toward said opening, a stop shoulder in said guide portions to be offset from the plane of movement of the coin and behind said discharge opening, the free end of said element having a chamfered edge engageable behind said protruding edge portion of a said coin in some manner adhered in the plate recess, whereby upon reverse rotation of the plate from the discharge position, the adhered coin is lifted by the chamfered edge into stop engagement of an edge of the coin with said stop shoulder to prevent complete return rotation of the plate with the coin therein which would permit repetition of said forward article-discharging rotation of the operating means.

2. In an article dispensing machine of the type including rotatable operating means and coin-releasable detent for locking said operating means against forward rotation which would dispense the articles, a coin lock comprising a casing having a coin-receiving slot therein, a plate

mounted in said casing to be rotatable with said operating means and having a coin-receiving recess in the edge thereof normally in registry with said coin-receiving slot in the locked position of the operating means, said casing having a coin-discharge opening for registry with said plate recess upon forward rotation of said plate with the operating means to a given discharge position thereof, said casing having guide portions intermediate said coin-receiving slot and coin-discharge opening for maintaining the coin in the coin-receiving recess of said plate, an elongated leaf-spring anchored at one end in said casing to extend freely forwardly along the path of forward movement of a coin in said plate recess to have the free other end presented toward said coin-discharge opening, said element having a portion yieldingly engageable with a peripheral edge of the coin protruding from said plate recess as it moves forwardly toward said opening, a stop shoulder in said guide portions to be offset from the plane of movement of the coin and behind said discharge opening, the free end of said leaf-spring having a chamfered edge engageable behind said protruding edge portion of a said coin in some manner adhered in the plate recess, whereby upon reverse rotation of the plate from the discharge position, the adhered coin is lifted by the chamfered edge into stop engagement of an edge of the coin with said stop shoulder to prevent complete return rotation of the plate with the coin therein which would permit repetition of said forward article-discharging rotation of the operating means.

3. In an article dispensing machine of the type including rotatable operating means and coin-releasable detent for locking said operating means against forward rotation which would dispense the articles, a coin lock comprising a casing having a coin-receiving slot therein, a plate mounted in said casing to be rotatable with said operating means and having a coin-receiving recess in the edge thereof normally in registry with said coin-receiving slot in the locked position of the operating means, said casing having a coin-discharge opening for registry with said plate recess upon forward rotation of said plate with the operating means to a given discharge position thereof, said casing having guide portions intermediate said coin-receiving slot and coin-discharge opening for maintaining the coin in the coin-receiving recess of said plate, an elongated leaf-spring mounted in said casing to extend freely along the path of forward movement of a coin in said plate recess and having a portion yieldingly engageable with a peripheral edge of the coin protruding from said plate recess, a stop shoulder in said guide portions to be offset from the plane of movement of the coin and behind said discharge opening, the free end of said leaf-spring having a chamfered edge engageable behind said protruding edge portion of a said coin in some manner adhered in the plate recess, whereby upon reverse rotation of the plate from the discharge position, the adhered coin is lifted by the chamfered edge into stop engagement of an edge of the coin with said stop shoulder to prevent complete return rotation of the plate with the coin therein which would permit repetition of said forward article-discharging rotation of the operating means, said leaf-spring being one end portion of an angularly bent length of spring strip material, an opposite end portion of which extends in said guide portions in the opposite direction to be yieldingly engageable with the peripheral edge of a said coin as it leaves said coin-receiving slot.

4. In an article dispensing machine of the type including rotatable operating means and coin-releasable detent for locking said operating means against forward rotation which would dispense the articles, a coin lock comprising a casing having a coin-receiving slot therein, a plate mounted in said casing to be rotatable with said operating means and having a coin-receiving recess in the edge thereof normally in registry with said coin-receiving slot in the locked position of the operating means, said casing having a coin-discharge opening for registry

with said plate recess upon forward rotation of said plate with the operating means to a given discharge position thereof, said casing having guide portions intermediate said coin-receiving slot and coin-discharge opening for maintaining the coin in the coin-receiving recess of said plate, an elongated leaf-spring mounted in said casing to extend freely along the path of forward movement of a coin in said plate recess and having a portion yieldably engageable with a peripheral edge of the coin protruding from said plate recess, a stop shoulder in said guide portions to be offset from the plane of movement of the coin and behind said discharge opening, the free end of said leaf-spring having a chamfered edge engageable behind said protruding edge portion of a said coin in some manner adhered in the plate recess, whereby upon reverse rotation of the plate from the discharge position, the adhered coin is lifted by the chamfered edge into stop engagement of an edge of the coin with said stop shoulder to prevent complete return rotation of the plate with the coin herein which would permit repetition of said forward article-discharging rotation of the operating means, said

leaf-spring being one end portion of an angularly bent length of spring strip material, an opposite end portion of which extends in said guide portions in the opposite direction to be yieldingly engageable with the peripheral edge of a said coin as it leaves said coin-receiving slot, said guide portions including a rib on a wall of the casing and having angularly disposed slots receiving angularly disposed portions of said spring strip, separable means being provided on the casing for retaining said spring strip in said slots.
